UNITED STATES PATENT OFFICE.

ANDERS OLOF GEORG STENMARK AND ERIK ADOLF HEDBERG, OF SANDVIKEN,
SWEDEN, ASSIGNORS TO SANDVIKENS JERNVERKS AKTIEBOLAG, OF SAND-
VIKEN, SWEDEN, A CORPORATION OF SWEDEN.

SAW BOW.

1,411,590.

Specification of Letters Patent.

Patented Apr. 4, 1922.

Application filed February 10, 1921. Serial No. 443,779.

To all whom it may concern:

Be it known that we, ANDERS OLOF GEORG STENMARK, a subject of the King of Sweden, and resident of Sandviken, in the Kingdom 5 of Sweden, and ERIK ADOLF HEDBERG, a subject of the King of Sweden, and resident of Sandviken, in the Kingdom of Sweden, have invented certain new and useful Improvements in Saw Bows, of which the following 10 is a specification, reference being had thereto in the accompanying drawing.

The present invention relates to a stretching-device for saw-bows, comprising a lever, pivotally connected with the saw-bow and by 15 means of a link connected with the saw-blade, which lever serves to stretch the saw-blade.

According to our invention the lever is arranged centrally in the end of the saw-bow, 20 which for this purpose is slotted. The slot in the saw-bow is of such length, that when the blade is stretched the lever will enter into the slot and will thus be concealed in the end of the saw-bow.

25 The arrangement is shown in the accompanying drawing where Fig. 1 shows a saw according to our invention. Figs. 2 and 3 show on a larger scale that end of the saw-bow which is provided with the stretching-device respectively in side elevation and plan-view. Figs. 4, 5 and 6 are detail-views.

One end of the saw-blade A is usually attached to one end of the saw-bow B, while the other end of the blade is attached to the 35 stretching-device which is provided at the opposite end of the bow. The stretching-device comprises a link C, one end of which is pivotally connected with the blade A by means of a pivot H and the other end of 40 which is pivotally connected with the shorter arm D of a bell-crank lever D, D¹ by means of a pivot F, said lever being pivotally connected with the saw-bow by means of a pivot G. The lever D, D¹ is, as shown in Fig. 5, 45 made of a plain piece of sheet-iron and is supported inside the lower fork-shaped end of the saw-bow. A longitudinal slot K is provided in the outer side of the tubular saw-bow intended for the lever arm D¹, said arm being completely entered and hidden in the 50 slot when the lever and the saw-blade are stretched. The arm D¹ is provided with an abutment E at its outer, free end, which as shown in Fig. 5, is formed by a deflected lap

of the sheet, which forms the lever. Said lap 55 abuts against the outside of the saw-bow thereby to prevent the arm D¹ from entirely entering the tube through the slot K, and to serve as a handle for manually withdrawing the arm from said slot.

With our invention the distance between the pivots F and G can be varied without difficulty within very wide limits in order to effect a suitable tension in the saw-blades for which the bow is intended. The form of 60 the lever D, D¹ also will be simple and easily made and its longer arm D¹ in its stretched position is concealed within the handle so as to leave a free place for the grasp of the hand around the bow.

Having now described our invention, what we claim is new and desire to secure by Letters Patent is:

1. A hack saw, comprising, in combination, a bow formed of tubular stock and 75 bifurcated at one end thereof, a bell-crank lever pivoted between the bifurcations of said bow, a saw-blade secured at one end thereof to the end of the bow opposite said bifurcated end, and a link pivotally connect- 80 ing the opposite end of said blade with one arm of said lever, the bow being provided with a slot at its bifurcated end for receiving the other arm of the lever whereby said arm when in operative position is concealed with- 85 in the bow.

2. A hack saw, comprising, in combination, a bow formed of tubular stock and bifurcated at one end thereof, a bell-crank lever formed of sheet metal and pivoted be- 90 tween the bifurcations of said bow, a saw- blade secured at one end thereof to the end of the bow opposite said bifurcated end, and a link pivotally connecting the opposite end of said blade with one arm of said lever, the 95 bow being provided with a slot at its bifurcated end for receiving the other arm of the lever whereby said arm when in operative position is concealed within the bow, said arm being provided with an angular portion 100 forming a stop for preventing the lever from completely entering said slot and forming a handle for manually withdrawing the arm from the slot.

In witness whereof we have hereunto 105 signed our names.

ANDERS OLOF GEORG STENMARK.
ERIK ADOLF HEDBERG.
